SHEET METAL ROOFING

Verdon Thomas Renner, Parkersburg, W. Va., assignor to The Parkersburg Iron and Steel Company, Parkersburg, W. Va., a corporation of West Virginia

Application February 25, 1936, Serial No. 65,591

2 Claims. (Cl. 108—18)

This invention relates to sheet metal roofing, and more particularly to lapped joints for such roofing wherein longitudinal crimps are provided along opposite edges of roofing sheets in position 5 to overlap in nested relation.

A general object of the invention is to provide an improved lapped joint for roofing sheets.

More particularly, objects of the invention are to provide a lapped roofing joint having improved 10 water-proofing characteristics in which means are provided for preventing or retarding the seepage of water between the lapped sheets and for draining such water as may get between them, and which is rigidly able to withstand nailing or other crushing forces, and has a number 15 of alining surfaces on the lapped members so positioned as to assure easy and accurate assembly.

Further objects of the invention are to provide 20 a lapped joint having advantages such as those described above, in which the special bends or corrugations providing the waterproofing, rigidifying and alining features are few in number and may be confined to one crimped member, 25 and in which the smaller and more abrupt bends are formed adjacent the terminal edge of such member where the material is easier to handle and where reasonable tolerance can be permitted in the location of such terminal edge 30 without impairing the functions of the joint.

Other objects of the invention will in part be 35 obvious and will in part appear hereinafter.

The invention accordingly comprises the features of construction, combination of elements 35 and arrangement of parts, which will be exemplified in the construction hereinafter set forth and the scope of the invention will be indicated in the claims.

For a fuller understanding of the nature and 40 objects of the invention reference should be had to the following detailed description taken in connection with the accompanying drawing, in which:

Fig. 1 is a fragmentary perspective view showing 45 adjacent roofing sheets embodying features of the present invention; and

Fig. 2 is a fragmentary transverse vertical sectional view taken through an overlapped joint embodying features of the invention.

The present invention is generally applicable 50 to sheet metal roofing having longitudinal crimps or corrugations adapted to nest in overlapping relation at opposite edges of each sheet. In the preferred form of the present construction, an 55 improved configuration is given to one lapped

crimped member of each sheet and the remaining crimps of such sheet may preferably be of simple inverted V construction, such as that which is conventionally used in 3—V or 5—V crimped roofing.

Referring more particularly to the drawing, there is shown in Fig. 1 a series of sheet metal roofing members 10, each of which terminates at one edge in an overlapping member and at the opposite edge in a crimped member which is adapted to nest within the overlapping member of an adjacent sheet to form a lapped joint. The overlapping member comprises an outer inclined leg 11 which may, if desired, terminate in a short horizontal flange 11' which affords an added support or rest for the leg 11. This flange 11' is not strictly essential, however, and may be omitted as shown in Fig. 2. The overlapping member has an inner oppositely inclined leg 12 joined to leg 11 by a crown portion 13 which, as illustrated, is desirably of upwardly convex curved shape, the entire overlapping member being of simple inverted V formation having smooth sides or legs.

The lapped member comprises an upwardly sloping leg 14 which extends from the main body of its sheet 10 and is in full surface contact with leg 11 at at least its upper and lower portions. The intermediate portion of leg 14 is dished inwardly as at 15 to provide a space which is sufficiently wide to disrupt capillary elevation between the lapped legs. This space also provides an air vent which tends to prevent syphoning of rain water between the sheets. The leg 14 merges into a crown portion 16 which is preferably of concentric curvature with the crown portion 13 and in full surface contact therewith, although this full surface contact is not strictly essential so long as the two crown portions contact at one or more points in supporting relation 40 so that flattening forces on the outer crown are transmitted, at least in part, to the lapped crown. The crowns also need not be convex, if a flat nailing surface is preferred. This lapped crown 16 merges into an upright leg 17 which is substantially vertical or only slightly tilted outwardly toward the terminal edge of the lapped member in order to provide a support against nailing or other crushing forces. At its lower end, the upright leg 17 merges with an inverted V-shaped foot comprising an inner side 18 which is bent upwardly from the leg 17 and forms therewith a drainage trough which is effective to discharge any water which may have seeped or been forced by wind beyond the air space at 15. The 55

underside of such trough, which is in the form of a curved corrugation, rests at 18 against the roof sheathing. The side 18 extends up into contact with the lower base portion of the overlapping leg 12, and from this point the foot extends downwardly at 20 in parallel relation and full surface contact with such leg 12. The terminal edge of the side 20 preferably rests against the roof sheathing, or at least extends sufficiently toward the latter to prevent any material flattening of the trough 17-18.

The several special bends provided in the lapped member are of simple and comparatively gently curved formation and are few in number so that the specially prepared crimping may readily be manufactured by means of simple and economical dies. Further, the shorter and more abrupt bends at the sides 18 and 20 of the small foot adjacent to the lower end of leg 17, are comparatively easy to make because they are located near the terminal edge of the sheet material, where it is easier to bend and handle. It will also be seen that reasonable tolerance in the crimping operations can be permitted without giving undue care to the ultimate position of the extreme edge of side 20, since either the latter or the trough at 19, and usually both, will afford a solid footing for the upright supporting leg 17. The downwardly extending side 20 is in extended surface contact with leg 12, and, in conjunction with the mating surfaces between legs 11 and 14, and the crowns 13 and 16 if the latter are in surface contact, serves properly to align the lapped members. As is best shown in Fig. 2, it will be seen that strains due to nailing or other downward crushing forces are resisted by the upright leg 17, and that any tendency of the latter to spread outwardly is counteracted by the surface contact between the foot at 20 and the overlapping leg 12. The lapped joint also effectively prevents water from reaching the roof sheathing, because of the channel at 15 and the drainage trough at 19.

It will be seen that there has been provided a construction which is well suited to fulfill its intended functions. Since certain changes may be made in the above construction and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent is:

1. A lapped joint for sheet metal roofing, comprising adjacent sheets, one of which is provided at one edge with an overlapping inverted V-shaped member having a convex crown portion and adjoining straight flat sides, and an unsymmetrical lapped member on an edge of the adjacent sheet; said lapped member consisting of a crown portion for nesting in and supporting said convex crown portion and adjoining major and minor legs, said major leg sloping upwardly from the sheet and having a preponderance of its surface in direct contact with the overlapping terminal leg, and a minor portion of said surface out of contact with said leg, and a base margin in surface contact with the terminal margin of said terminal leg, said minor leg sloping downwardly and provided with a terminal formation comprising a relatively small inverted U-shaped foot connected to said minor leg by a U-shaped drainage trough, the outer side of said foot being of plane formation and providing a terminal surface in direct contact with the base portion of the remaining leg of said overlapping member. 25

2. A lapped joint for sheet metal roofing, comprising adjacent sheets, one of which is provided at one edge with an overlapping inverted V-shaped member having a convex crown portion and adjoining straight flat sides, and a cooperating unsymmetrical lapped member on an edge of the adjacent sheet; said lapped member consisting of a crown portion for nesting in and supporting said convex crown portion and adjoining major and minor legs, said major leg sloping upwardly from the sheet and having a preponderance of its surface in direct contact with the overlapping terminal leg and a minor portion that is dished inwardly out of contact with said overlapping terminal leg, and a base margin in surface contact with the terminal margin of said terminal leg, said minor leg sloping downwardly and provided with a terminal formation comprising a relatively small inverted U-shaped foot connected to said minor leg by a U-shaped drainage trough, the outer side of said foot being of plane formation and provided with a terminal surface in aligning surface contact with the base portion of the remaining leg of said overlapping member. 30 35 40 45 50
